UNITED STATES PATENT OFFICE.

WILLIAM W. RIDGELY, OF SYRACUSE, NEW YORK, ASSIGNOR, BY MESNE ASSIGNMENTS, TO RIDGELY HEATER COMPANY, OF SCRANTON, PENNSYLVANIA, A CORPORATION OF NEW JERSEY.

HEATER.

Application filed September 12, 1925. Serial No. 56,038.

This invention relates to heaters and refers more particularly to the construction of the fire box for burning various grades of hard and soft coal and other solid fuel, reference being had to my Patent No. 1,648,622, Nov. 8, 1927, and my pending application Serial No. 43,799, filed July 15, 1925.

The main object of the invention set forth in each of these applications is to provide a supplemental fire pot composed of sections of such construction that they may be assembled in the combustion chambers of different types of furnaces and analogous house heaters for receiving the fuel and in such manner that the air necessary for supporting combustion may circulate entirely around all sides of the confined fuel including the top and bottom thereof and also through the fuel at any level resulting in a more complete combustion of the solid and gaseous fuels and therefor a more complete incineration of the solids so that the residue is reduced to a relatively small quantity of fine ash.

Another object is to permit the burning of the cheaper grades of bituminous coal with a negligible escape of gas or smoke, considerably below the limitations prescribed by the smoke ordinances of the more exacting municipalities.

One of the specific objects of the present device is to increase the grate area of the fire pot by making the bottom thereof conical with its apex uppermost and at the same time to utilize this conical bottom as a means for automatically feeding the fuel from the center toward the sides of the fire pot and thereby to greatly increase the supply of air to the burning fuel at different levels for complete combustion of the gases as well as the solids at all levels.

Another object is to support the bottom conical section of the fire pot in such manner that it may be shaken angularly about its vertical axis without disturbing the remaining sections of the fire pot.

Another object is to provide the conical bottom with agitator arms or lugs projecting from the upper face thereof for angular adjustment therewith to facilitate the agitation and removal of the fine ash during the shaking operation.

A further object is to provide the conical bottom with one or more vertically tilting sections normally held in place by one of the

operating parts of the shaking device so that by simply withdrawing said part the tilting section will automatically open for dumping the fuel from the fire pot when necessary.

Other objects and uses relating to specific parts of the device will be brought out in the following description:

In the drawings:

Figure 1 is a top plan view of my improved fire pot detached from the furnace showing a portion of the shaker shaft.

Figure 2 is a vertical sectional view of the same device taken on line 2—2, Figure 1, showing portions of the combustion chamber of a heater in which the fire pot is located and the position of the fire pot relatively to the walls of the combustion chamber.

Figure 3 is a horizontal sectional view taken in approximately the plane of line 3—3, Figure 2 with conical grate removed, showing more particularly the spider frame for supporting the sectional sides and bottom of the fire pot.

Figure 4 is a detail vertical sectional view taken in the plane of line 4—4, Figure 3, showing the upper portion of the conical grid bottom and its tubular supporting stem in operative position upon the supporting frame.

Figure 5 is a detail horizontal sectional view through adjacent edges of two of the side sections of the fire pot showing the manner of assembling those sections.

Figure 6 is a perspective view of one of the detached side sections of the fire pot.

Figure 7 is a top plan view of a portion of a slightly modified form of my invention in which an air and gas deflecting plate is used directly over the sectional sides of the main fire pot.

Figure 8 is a vertical sectional view taken on line 8—8, Fig. 7.

The device forming the subject matter of this invention is adapted to be placed in the combustion chamber as —A— of a furnace or other solid fuel heater and comprises a base section —1— and a circular fire pot composed of upright sections —2— and a conical bottom section —3— together with suitable means including a shaker-rod —4— for shaking the bottom section —3— angularly about its vertical axis.

The base or grate-supporting section —1— is preferably of a skeleton type consist-

ing of a central hub having vertically spaced co-axial center rings or bearings —5— and —5'— rigidly connected to each other by diametrically opposite upright bars —6—, the 5 lower ring being provided with diametrically opposite pairs of arms —7— in the same sides as the upright bars —6— and equally spaced from and around the axis of the rings.

These arms —7— are preferably of equal 10 length and are provided at their outer ends with lugs —8— adapted to rest upon the upper faces of suitable bearing lugs —9— projecting inwardly from the upright walls of a combustion chamber —A— near the lower 15 end thereof as shown more clearly in Figure 2.

The portions of the arms —7— adjacent the inner ends of the lugs —8— are provided with circumferentially elongated slots or 20 sockets —10— which extend vertically therein and are arranged equal distances from the axis of the rings —5— and —5'— and are also spaced equal distances apart circumferentially for receiving portions of the lower ends 25 of the upright sections —2— and holding them in properly assembled relation against circumferential movement relatively to the base section —1—.

The rings —5— and —5'— are provided 30 with vertically aligned openings therethrough preferably of the same diameter for receiving a central tubular stem 16 of the conical bottom section —3— and permitting the latter to be turned about the axis of the rings 35 by the shaker bar or rod —4—, the arms —7— being preferably inclined outwardly and upwardly from their junction with the lower ring —5— so that their outer ends will be disposed in a horizontal plane substantially 40 midway between the rings and at the same time allowing the central portion of the support —1— to extend to a plane near the junction of the combustion chamber —A— with the ash pit not shown and also allowing the 45 lower end of the fire pot to extend relatively close to the ash pit.

The object in making the base section —1— of skeleton or spider form is to provide relatively large air spaces for the free circulation 50 of air from the ash pit upwardly through practically the entire area of the bottom section —3— and also through and around the main body of the fire pot composed of the sections —2—.

These sections —2— are of similar construction and are therefore interchangeable and, as shown more clearly in Figure 6, each section is curved circumferentially so that when assembled upon the base section 60 —1— they will be concentric with the axis of the rings —5—.

Each section is of sufficiently small size to permit it to be inserted through the fuel door or ash door and is tapered from top to bottom 65 or flaring from bottom to top and is pro-

vided with a plurality of, in this instance three, circumferential rows of vertical slots or apertures —11—, —11'— and —11''— leaving intervening connecting webs —12— between the several rows. 70

These slots are relatively narrow and arranged in uniformly spaced relation circumferentially, the slots of each row being of uniform vertical length.

These slots serve as passages for the inlet 75 of air to support combustion and also permit the escape of fine ash therethrough to the ash pit, the slots of the lower row being open in the bottom while the slots of the upper row are open at the top to facilitate the free 80 passage of fine ash and air therethrough.

When the sections —2— are assembled on the supporting base —1— the outer faces of their upper ends contact with the walls of the combustion chamber to assist in holding 85 the sections in operative position while the remaining portions are spaced apart from said walls to afford a clear open space for the passage of air from the ash pit or bottom upwardly around the fire pot and through 90 the slots of the several rows.

This provides for the supply of a large quantity of air for supporting combustion at all levels of the fire pot, all of which greatly facilitates the complete combustion of the 95 solid fuel and gases to such an extent as to eliminate objectionable smoke and to reduce the solid fuel to a relatively small quantity of fine ash and at the same time obtains from the fuel a maximum amount and degree of 100 heat and permits the economic use of the cheaper grades of bituminous coal, coke, and the finer grades of anthracite coal.

The lower ends of the several sections —2— are provided with pendant posts —13— 105 adapted to enter the sockets —10— in the base section —1—, each socket serving to receive the posts on the edges of adjacent sections for holding said sections in operative position against movement relatively to the base section without other fastening means. 110

Corresponding edges of the intermediate portion of each section are provided with circumferentially extending lugs —14— offset outwardly to overlap upon the edge of the 115 next adjacent section for additionally holding the sections against inward and outward displacement when adjusted for use.

The bottom section —3— is conical or "mushroom" shape in side elevation and is of 120 slightly less diameter than the internal diameter of the lower end of the upright portion of the fire pot so that it may be placed in operative position from the top downwardly through said upright portion or, if desired, 125 may be placed in operative position from the bottom upwardly through the ash pit before the side sections are installed.

This conical bottom section is arranged 130 with its apex uppermost and co-axial with

the rings —5— and —5'— and is provided near its apex with a central hub —15— having its lower end resting upon the upper face of the upper ring —5'—.

5 A tubular post or stem —16— has its upper end secured by a cross pin —17— to and within the hub —15—, said post being extended downwardly through the rings —5— and —5'— and some distance below the lower 10 ring —5— for relative rotation in said rings, the lower end of the post being provided with a diametrically extending opening —17— for receiving the reduced end —4'— of the shaker rod —4—.

15 The conical bottom section —3— is also provided with a plurality of circumferential rows of radial slots —18—, —19— and —20— arranged in different planes one about the other in spaced relation to permit the passage of air therethrough for supporting combustion and also to allow the escape of fine ash therethrough to the ash pit, the lower row of slots being open at the bottom while the upper series of slots —20— are arranged 20 directly over the opening in the tubular stem —16— for the same purpose.

The conical bottom section —3— is provided with a relatively movable tilting section —21— having its lower outer edge 30 formed with opposite circumferentially projecting trunnions —22— journaled in suitable bearings —23— which are open at the top to permit the section —21— to be easily and quickly installed or removed without dis- 35 placing any of the other parts.

40 The tilting section —21— is provided with a downwardly and inwardly projecting arm —24—, having its lower end normally resting upon the upper face of the shaker bar —4— adjacent the tubular stem —16— for holding the tilting section in its closed position and permitting it to be opened by simply withdrawing the shaker rod —4— forwardly 45 from the tubular stem —16— whereupon the movable section —21— will automatically open by its own weight to the position shown by dotted lines in Figure 2 for partially or wholly dumping the ash and fuel from the fire pot when desired.

50 The conical section —3— is also provided with a series of agitator blades or fins —25— arranged in more or less staggered and spaced relation around the axis thereof and projecting upwardly therefrom, said agitator blades being preferably formed separately from the conical section —3— and secured in suitable sockets —26— therein as shown in Figure 2.

60 In Figures 7 and 8, is shown a deflecting ring composed of sections —27— arranged end to end circumferentially around the upper end of the fire pot so as to incline downwardly and inwardly for deflecting the heated air rising around the fire pot downwardly and inwardly on to the surface of

the fuel for increasing the combustion of the gases which tend to accumulate at said surface and thereby to further reduce the smoke content of the escaping products of combustion in addition to the extra heat produced by the burning of the gases.

In this latter construction the upper ends of the upper row of slots as —28— will be closed and the inner walls of the combustion chamber as —A'— will be corrugated circumferentially at —29— while the upper outer edge of the deflector ring —27— will also be corrugated at —30— to mesh with the corrugations —29— and thereby to retard the escape of gases at the corrugated joint.

The sections —27— of the deflector ring are provided with suitable legs —31— adapted to engage the upper portion of the fire pot for holding said deflector plates in spaced relation thereto as shown more clearly in Figure 8, the meeting ends of the sections being provided with interlocking tongue and groove connections to hold the sections against relative lateral displacement.

It will be noted upon reference to Figure 2 that the apex of the conical bottom section —3— extends some distance above the bottom of the upright sections which allows the fuel to automatically feed downwardly from the center toward the sides and thereby to distribute itself over a relatively larger area than would be possible if the bottom section were flat and also permitting the air surrounding the fire pot to pass more readily into the burning fuel for supporting combustion at the various levels, it being understood that the air may pass not only through the openings in the bottom section but also through the side sections from bottom to top and that the natural flow of the heated air entering the side sections would follow upwardly along the inclined sides of the bottom section.

This upward and inward feed of the air is further facilitated by the downwardly tapered form of the fire pot and assures the feeding of the heated air to the fuel at different levels, it becoming heated to gradually increasing degrees as it rises.

In case the ash and fuel should become congested on the bottom section —3—, the latter may be shaken angularly about its axis by means of the operating means —4— which may extend to the exterior of the furnace for that purpose.

During this shaking operation the fins —25— serve to break up the congestion and fuel on the grate and allows it to sift through the openings therein to the underlying ash pit.

In dumping the ash and fuel from the fire box, the shaking member —4— may be withdrawn from the tubular stem —16— thus permitting the tilting section —21— to drop to an open position as shown by dotted lines in

Figure 2 under which conditions the ash and fuel will fall through the opening.

In assembling the parts the base section 1— is first placed in operative position up-
5 on the lugs—9— where it may be held against turning by any suitable fastening means. The bottom section —3— may then be placed in operative position upon the base section and supported thereon independently of any
10 other fastening means than the insertion of the tubular stem —16— into the rings —5— and —5'— so that the hub —15— of the bottom section may rest upon the top of the upper ring.

15 The side sections —2— may then be placed in operative position upon the base section —1— with the posts —13— seated in their respective sockets —10— without any other fastening means for holding said sections in
20 operative position with their upper ends resting loosely against the walls of the combustion chamber or against the lugs —14—.

It is evident however that the order of installation of the bottom section and side sections may be reversed and that in either case
25 the sections may be placed in operative position or removed thru either the fuel door or ash door of the heater.

What I claim is:

30 1. In a heater of the character described, a combustion chamber, a fire pot mounted in the combustion chamber and provided with a co-axial upwardly tapered bottom section movable angularly about its axis relatively
35 to the side walls of the fire pot for shaking the ashes therefrom, said bottom section being provided with a tiltable section and removable means for moving the bottom section angularly and for holding the tilting
40 section in its closed position when adjusted for use, said tilting section being adapted to open by its own weight when said means is removed.

45 2. In a heater of the character described, a base having a central hub and grate-supporting arms projecting outwardly there-

from in spaced relation circumferentially to form relatively large air and ash passages between them, the outer ends of said arms being provided with sockets equal distances from
50 the axis of the hub and in uniformly spaced relation circumferentially about said axis, and a fire box composed of a number of sections corresponding to the number of said arms arranged edge to edge circumferentially
55 and having the lower ends of their meeting edges alined with the centers of the sockets and provided with pendant lugs seated in said sockets.

3. A heater as in claim 2 in which a center
grate is rotatably supported on said hub and has its outer marginal edge disposed in approximately the horizontal plane of the socketed outer ends of the grate-supporting arms and in spaced relation to the lower end of
60 the firebox.

4. In a heater, a grate-supporting base having a central hub and a series of sockets arranged in uniformly spaced relation circumferentially around the hub and equal distances from the axis thereof, a firebox composed of sections arranged edge to edge circumferentially around the hub with the meeting edges in vertical alinement with said sockets and provided with pendant lugs seated
70 in adjacent sockets, a tubular post journaled in said hub for angular movement and extended some distance above and below the horizontal plane of the socketed portions of
75 said base, a conical center grate having its apex secured to the upper end of the post and engaged with the upper end of the hub and its outer marginal edge disposed in approximately the horizontal plane of the socketed portions of the base, and means operatively connected to the lower end of the post for
80 effecting angular movement of the post and center grate.

In witness whereof I have hereunto set my hand this 20th day of August, 1925.

WILLIAM W. RIDGELY.
